LEON I. LIPTON, OF NEW YORK, N. Y., ASSIGNOR TO TAUER LIPTON & CO., INC., OF NEW YORK, N. Y., A CORPORATION OF NEW YORK.

REVERSIBLE CUFF.

Application filed May 31, 1923. Serial No. 642,587.

To all whom it may concern:

Be it known that I, LEON I. LIPTON, a citizen of the United States, and a resident of the city of New York, borough of Manhattan, in the county and State of New York, have invented new and useful Improvements in Reversible Cuffs, of which the following is a full, clear, and exact description.

10 This invention relates to reversible shirt cuffs.

The general object of the invention is the provision of a simply constructed, reversible cuff that may be folded one way to simulate 15 a plain cuff and the opposite way to simulate a turnover cuff.

A further object of the invention is the provision of a reversible cuff capable of being folded in either direction to simulate 20 two different types of cuff, and provided with means for attaching the opposite edges when folded to simulate either type of cuff.

These objects are accomplished by providing a cuff body, forming in the cuff body a 25 transverse plait, dividing the cuff into an inner fold and an outer fold so that when the outer fold is turned in one direction the body simulates a plain cuff and when folded in the other direction simulates a turnover 30 cuff, and providing means for attaching the opposite edges of the folds.

These and other objects of the invention will be more clearly understood from the following detailed description and accompanying drawings.

Figure 1 is a top plan view of the cuff when unfolded;

Figure 2 is a side elevation of the cuff when unfolded;

40 Figure 3 shows the cuff folded to simulate a turnover cuff;

Figure 4 is an elevation of the cuff showing it folded to simulate a plain cuff and with its opposite edges connected.

45 Figure 5 is a section along the line 5—5, Figure 3.

Referring to the above-mentioned drawings, the invention includes a cuff body 10 in which a transverse plait 11 is formed near 50 the center line of the cuff. This transverse plait 11 divides the cuff into a fold 12 and a fold 13. The inner edge of the fold 13 is attached to a shirt sleeve 14 by lines of stitches 16. The outer edges of the body 55 10 is defined by a hem 15.

The position of these folds as shown in Fig. 5 indicates that the fold 12 is bent over the adjoining edge of the outer-fold and extends downwardly along the outside of the cuff to simulate a turned-down cuff. In this 60 position a portion of the fold 12 overlaps the joining edge of the outer-fold to present a clean, fresh surface. When, however, the fold 12 is folded within the fold 13, as indicated in Fig. 4, then the cuff has the appearance of a plain cuff. By providing the line of stitching joining the fold 12 on the inside and the fold 13 just beneath the line of union between the two folds, I am enabled to turn over the fold 12 in the manner 70 shown in Fig. 5 to present a smooth, clean overlapping edge portion.

In forming the cuff body, the ends 17 and 18 of the fold 12 are curved inward toward the fold 13 as shown in Figure 1. By 75 thus curving the ends of the fold 12 as they approach the fold 13 the fold 12 is not visible when turned beneath the fold 13 to simulate a plain cuff. The fold 12 is greater in depth than the fold 13 so that when the 80 fold 12 is turned over the plait 11 the outer edge of the fold 12 extends to the inner edge of the fold 13. Buttonholes 19 are provided in the fold 12 so that the opposite edges may be connected by any ordinary 85 cuff link or button.

The outer corners of the fold 13 are cut away as shown at 20 so that when the fold 12 is turned over the plait there will be no 90 corners of the fold 13 projecting beyond the fold 12. A plurality of buttonholes 21 are formed in one end of the fold 13 for receiving buttons 23 attached to the opposite end, providing a means for connecting the opposite ends or edges of the fold 13 when the cuff body has been folded to simulate a plain cuff.

When it is desired to use a shirt provided with cuffs of this type, the wearer may select which type of cuff he prefers for different occasions. If the wearer prefers a plain cuff he merely turns the fold 12 beneath the fold 13 and the cuff body simulates a plain cuff. In this case the opposite ends or edges are attached by means of the buttons and buttonholes 21. When it is desired to make the cuff body simulate a turnover cuff the fold 12 is folded over the plait 11 as shown in Figure 3.

In order to attach the opposite ends of the 110

fold 12 when the cuff is folded to simulate a turn-over cuff the ends of the fold 13 are overlapped and a cuff link or cuff button inserted into the buttonholes 19. When 5 the cuff is folded to simulate a turn-over cuff the opposite edges of the fold 13 may be first connected by means of the buttons 22 and buttonholes 21, and then the opposite edges of the fold 12 connected by inserting 10 a cuff link into the button holes 19 in the usual manner.

I would state in conclusion that while the illustrated example constitutes a practical embodiment of my invention I do not limit 15 myself strictly to the exact details herein illustrated since manifestly the same can

be considerably varied without departing from the spirit of the invention as defined in the appended claim.

Claim.

A reversible cuff construction, which comprises a cuff body folded transversely along a line intermediate the edges to form a folded edge, and a line of stitching along the fold near the edge thereof passing 20 through both walls forming such fold whereby one portion of the cuff may be bent over the line of fold to extend down along the outside of the other portion to 25 present a fresh clean edge portion.

LEON I. LIPTON.
